UNITED STATES PATENT OFFICE.

OLIVER P. SCHRIVER, OF NEWPORT, KENTUCKY.

DESIGN FOR A COVERED CURB FOR CHAIN-PUMPS.

SPECIFICATION forming part of Design No. 24,116, dated March 12, 1895.

Application filed January 18, 1895. Serial No. 535,414. Term of patent 7 years.

To all whom it may concern:

Be it known that I, OLIVER P. SCHRIVER, a citizen of the United States, residing at Newport, in the county of Campbell and State of Kentucky, have invented and produced a new and original Design for a Chain-Pump Curb; and I do hereby declare the following to be a full, clear, and exact description of the same, reference being had to the accompanying drawings, which form a part of this specification.

My invention relates to a new and original design for a covered curb for chain-pumps, and is fully represented in the annexed drawings, in which—

Figure 1 is a side elevation of said covered-curb. Fig. 2 is a plan of the curb proper. Fig. 3 is a plan of the cover.

The covered curb has a flat front A, outwardly-bowed sides B, B', and a rounded-back C. The cover for said curb has a flat front a; outwardly-bowed sides b, b', a rounded back c, and a crowning top D.

I claim as my invention—

The design for a covered curb for chain-pumps, substantially as herein shown and described.

In testimony whereof I affix my signature in presence of two witnesses.

OLIVER P. SCHRIVER.
